(57) **CLAIM**

We claim the ornamental design for a bottle, as shown and described.

DESCRIPTION

FIG. 1 is a top, front, and left side perspective view of a bottle showing our new design;

FIG. 2 is a top, front, and right side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof, shown in an enlarged condition; and,

FIG. 8 is a bottom plan view thereof.

The broken lines shown in the drawings are included for the purpose of showing environmental structure that forms no part of the claimed design.
